CATHODE

Frederick W. Lyle, Wilkinsburg, Pa., assignor to Westinghouse Electric & Manufacturing Company, East Pittsburgh, Pa., a corporation of Pennsylvania

Application March 19, 1938, Serial No. 196,955

4 Claims. (Cl. 250—27.5)

My invention relates to incandescent helically-wound metallic ribbons and, in particular, to such ribbons used as electron-emissive cathodes in electrical discharge devices.

One object of my invention is to insure that a helical edgewound metallic ribbon, which is heated by electric current flowing therethrough, shall operate as nearly as possible without variation in temperature radially from the inner to the outer edge of the ribbon.

Another object of my invention is to insure that helical edgewound metallic ribbons employed as directly-heated electron-emissive cathodes for electrical discharge devices shall vary as little as possible in electron emissivity between radially inward and radially outward sections of the cathode surface.

Other objects of my invention will become apparent from the following specification, taken in connection with the drawing in which:

Figure 1 shows, in side elevation, a typical helical edgewound ribbon cathode for an electrical discharge device;

Fig. 2 shows an end elevation of the same cathode;

Fig. 3 shows a cross-section of the cathode ribbon along line III—III of Fig. 2.

Fig. 4 shows an end view of a similar cathode embodying a modified form of terminal connection; and

Fig. 5 shows, in side elevation, a short section of one end of the cathode illustrated in Fig. 4.

One form of incandescent thermionically-emissive cathode which has been very successfully used for electrical discharge tubes of comparatively large current rating comprises a ribbon of some suitable metal 1, such as nickel, or a nickel-cobalt-titanium alloy known to the trade as Konal, which is wound into a helix with the broad dimension of the ribbon approximately perpendicular to the axis of the helix. The ends of the ribbon 1 are usually welded to heavy metallic leads 2 which are sealed through the glass wall of an evacuated container, and which supply electric current to heat the helix to an incandescent temperature. Before installation in the tube, the helix is usually coated with a mixture of barium and strontium oxides or other materials which are well known in the art to freely emit electrons when raised to an elevated temperature. It has been found that both the winding of the helix and its subsequent operation are improved if, before winding, the ribbon is slightly crimped, which may be done by passing it between a pair of toothed rollers.

It has been customary in the prior art to employ a ribbon having the same thickness throughout its width, but it can be shown that helices made up from such ribbon tend to operate with a higher temperature at their radially inward edge than at their radially outward edge. Since electron emissivity in general varies with a rather high power of the temperature of the emitting surface, it is desirable that all portions of a cathode surface shall operate at as high a temperature as 10 the material is able to withstand without being progressively destroyed by high temperature. It follows accordingly that the above-mentioned tendency of edgewound ribbon cathodes to operate with a higher temperature at their inner edges 15 than at their outer edges is a defect which results in an inefficient use of the radially outer portion of the electron-emitting surface.

In accordance with my invention, I so modify the form of the ribbon that its radially inner edge 20 operates at approximately the same temperature as its outer edge. One expedient which I employ for doing this is to roll the ribbon with a cross-section, illustrated in Fig. 3; namely, with a slightly wedge-shaped cross-section, so that the 25 inner edge of the helix is thinner than the outer edge. A ribbon of this cross-sectional form is adapted to be welded to terminal-studs, the ends of which are perpendicular to the axis of the ribbon, as illustrated in Fig. 2. Referring to the 30 latter figure, distances from the axis of the helix may be denoted by the letter r , and it will be noted that, in the case of an uncrimped ribbon, if a current path of infinitesimal width dr at a distance r from the axis be considered, the length 35 of this current path from one terminal to the other will be $2\pi Nr + 2L$, where N is the number of turns of the helix and L is the distance from the end of the terminal-stud to the plane of the helical axis. In the usual filament, N will be so large 40 compared with L that the term $2L$ may be neglected. In other words, current passing from one terminal-stud to the other through the current path of width dr at a distance r from the axis traverses a path of approximate length $2\pi Nr$. It 45 is obvious that the length of this path is greater for those portions of the ribbon where r is large than for those portions where r is small.

In a typical filament of the prior art in which the thickness of the ribbon was the same for all values of r , it is clear that currents traversing paths of width dr which were near the inner edge of the ribbon, and for which r was consequently small, traversed paths of smaller electrical resistance than currents traversing paths of similar 55

width dr near the outer edge of the ribbon. In other words, current density was greater in the radially inward portions of the ribbon than in the radially outward portions of the ribbon, and in consequence of this greater density of heating current, the radially inward portions of the ribbon tended to run at a higher temperature than the radially outward portions of the ribbon.

Where the axial distance between turns of the ribbon is comparatively large, it is apparent that the same temperature would be obtained for all values of r in the ribbon if the current density were made the same. Since the total resistance of a current path is proportional to the length thereof divided by the product of the thickness by the width dr ; that is to

$$A = \frac{2\pi Nr}{tdr}$$

where A is the resistance of the element of width dr at radial distance r , t is the thickness of the ribbon at radial distance r , and N is the number of turns, it is obvious that in order to make A constant for all values of r , t , the thickness of the ribbon, must be proportional to r . In other words, the cross-section of the ribbon should be a truncated triangle having a thickness at its inner edge in the same ratio to its thickness at the outer edge as the inner radius of the helix is to the outer radius of the helix.

Where the turns of the helix are more closely spaced, it may be that the tendency of adjacent turns to heat one another will cause a higher temperature at the inner edge of the helix than at the outer edge, with the result that the inner edge must be made somewhat thinner than the proportion outlined in the foregoing paragraph would indicate. Since calculation of such a problem in heat flow is quite complicated, it is probably easier as a practical matter to determine the proper relative thicknesses of the inner and outer edges of the helix in the case of closely wound filaments by trial and experiment. The general principle may, however, be followed that, where a given cross-section is found to produce too high a temperature in the radially inward portions of the ribbon, the inner edge of the ribbon should be thinned down; and vice versa.

Where the distance L in Fig. 2 is not negligible compared with $2\pi Nr$, the thickness of the ribbon should be proportional to $2\pi Nr + 2L$.

Another expedient than varying the thickness of the ribbon radially may be resorted to in certain cases where it is desirable, and this is illustrated in Figs. 4 and 5. Instead of making the

ends of the terminal-studs to which the ribbon is welded perpendicular to the axis of the ribbon, they may be slanted in the manner shown in Fig. 4 to such a degree that the length of the path of width dr at a distance r from the axis of the helix is the same for all values of r , in which case a ribbon of the same thickness throughout may be employed. It is obvious that the slanting of the ends of the terminal-studs and the varying of the thickness of the ribbon radially 10 are alternative devices for obtaining uniform, or any predetermined, distribution of current density radially in the ribbon, and that they may be used in combination with each other for that purpose as well as separately.

While I have described a particular embodiment of my invention, it is obvious that the principles thereof are of broader application in ways which will be obvious to those skilled in the art. I accordingly intend that the following claims shall be only limited insofar as is made necessary by their express terms taken in conjunction with the prior art.

I claim as my invention:

1. An incandescent cathode comprising a 25 helical edgewound metallic ribbon, the thickness of the ribbon at any point being proportional to the radial distance of said point from the axis of the helix.

2. An incandescent cathode comprising a 30 helical edgewound metallic ribbon, the thickness of the ribbon at any point being proportional to the radial distance of said point from the axis of the helix affixed to terminal leads at junctions which are approximately perpendicular to the 35 axis of the ribbon.

3. An incandescent directly-heated cathode comprising a helical edgewound ribbon having straight portions at the ends of the ribbon affixed to terminal-studs at junctions substantially perpendicular to the axis of the ribbon, the length of each said straight portion being L , the helix having N turns, and the thickness of the ribbon at distance r from the axis of the helix being proportional to $2\pi Nr + 2L$.

4. An incandescent directly-heated cathode comprising a helical edgewound ribbon affixed to terminal posts at junctions forming an angle with the axis of the ribbon, the length of any current path from terminal post to terminal post 50 through the ribbon at a distance r from the axis thereof being proportional to the thickness of the ribbon at the distance r .
